UNITED STATES PATENT OFFICE.

CHARLES F. BROWN, OF SALT LAKE CITY, UTAH.

RAILWAY ROAD-BED.

1,225,218.

Specification of Letters Patent.

Patented May 8, 1917.

Application filed March 13, 1917. Serial No. 154,630.

To all whom it may concern:

Be it known that I, CHARLES F. BROWN, a citizen of the United States, residing at Salt Lake City, in the county of Salt Lake 5 and State of Utah, have invented certain new and useful Improvements in Railway Road-Beds, of which the following is a specification.

My invention relates to railway tracks 10 and has for its object to provide a drained and paved roadbed which will prevent the disintegration of the pavement adjacent to rails.

These objects I accomplish with the im- 15 proved roadbed illustrated in the accom- panying drawings in which similar letters and numerals of reference indicate like parts throughout the several figures and as de- scribed in the specification forming a part of 20 this application and pointed out in the ap- pended claims.

In the drawings in which I have shown a substantial embodiment of my invention Figure 1 is a vertical section of a portion of the 25 roadbed and a rail thereon with a portion of a tie in dotted lines. Fig. 2 is a side elevation of one of the rail shields or cover plates. Fig. 3 is a transverse section of one of said 30 plates. Fig. 4 is a plan view of one of said plates or shields. Fig. 5 is a plan view of a portion of a railway track with portions of the shields cut away, and removed from the roadbed.

On paved streets and roads it has been 35 found extremely difficult to lay a railway track with the pavement close to the rails which pavement will not be disintegrated by water passing down at the sides of the rails and accumulating under the rails and ties, 40 and then freezing and expanding the ties, water and adjacent portions of the roadbed and bulging the pavement. The present invention is intended to direct the water from sprinkling, rains or melted snows downward 45 by the rails and ties and into a tile pipe or other drain pipe and away, thus removing the water from the roadbed before it has time to freeze, and consists of sheet metal angle plates C, which are placed adjacent to 50 the web and base flanges of the rails B. The said plates C have portions thereof struck as spacing lugs G from the inclosed angle side which lugs G bear against the web and base flange of the rails to space said plates 55 from the rails to allow water to pass downward by the rails when said rails are se-

cured on the ties Q. Portions of said plates are struck in the opposite direction to form the pavement engaging lugs H and J and whereby through the grouting and binding 60 material K the said plates C may be securely fastened to the pavement. Vertical openings D are provided in and through the concrete M to convey the water downward into and through the layer of pea gravel N, to be 65 carried away through the drain pipe A. In order that said openings D may not become clogged and to form a longitudinal water channel the lower portion of said plates C are curved upwardly as at E. 70

The roadbed is constructed by excavating the earth P and filling a portion of said ex- cavation with pea gravel N in which is laid a drain pipe A on one or both sides of the road as desired. Under the track portion 75 of the roadbed a bed of concrete T may be laid if desired. The bed of pea gravel N covers said concrete T as well as surround- ing the said drain pipe A. On the top of the layer of pea gravel is placed a bed of 80 concrete M with holes D formed therein which partially surrounds the ties Q. On a portion of the said concrete M adjacent the rails a grouting and binding material K is laid, a portion of which adheres to the said 85 lugs H and J of the angle plates C, and on which the pavement is laid, the kind shown being asphaltum and stone blocks. Adja- cent the tread of the rails stone pavement blocks L may be laid if desired or the asphal- 90 tum covering may fill the space shown as L.

Having thus described my invention I de- 95 scribe to secure by Letters Patent and claim:—

1. A railway roadbed consisting of a ce- 95 ment concrete layer having a plurality of vertical holes therethrough; ties resting in said concrete to support rails; spaced apart angle plates adjacent the web and base flanges of rails carried on said ties; lugs struck outwardly from said plates; and a 100 cementitious paving strata covering said concrete and engaging with said lugs and bearing against said plates.

2. A railway roadbed consisting of a layer of cement concrete having a plurality 105 of vertical openings therethrough; ties par- tially surrounded by and resting in said con- crete; angle plates spaced from rails fas- tened on said ties; lugs struck from said an- 110 gle plates to space them from the rails and to engage with a cementitious paving strata; a convex portion of said plates to form a wa-

- ter channel leading to said openings in said concrete; and a surface strata covering said concrete and abutting against the outer side of said plates at their upper edges.
- 5   3. A railway track consisting of a layer of gravel within which is placed a drain pipe; a layer of concrete on said gravel and having a plurality of vertical openings therethrough; ties partially surrounded by said concrete and resting on said gravel; rails fastened on said ties; opposed sheet metal angle plates spaced from the web and flange portion of said rails; lugs integral with said plates; a cement grouting engaging with said lugs and resting on said cement concrete; an arc shaped longitudinally disposed portion of said plates spaced above the openings in said concrete; and a surface

strata resting on and adhering to said grouting and concrete.

20

4. A railway roadbed comprising a drainage layer of gravel; a drain pipe therein; a layer of concrete on said gravel and having a plurality of openings therethrough; opposed sheet metal plates having a portion of each curved upwardly as a covering for said openings in said concrete; lugs struck from said plates; a cement grouting engaging with and adhering to said lugs; and a surface strata supported by said concrete 25 and grouting.

25

In testimony whereof I have affixed my signature in presence of a witness.

CHARLES F. BROWN.

Witness:

SAM RANEY.
